UNITED STATES PATENT OFFICE.

HENRY LOOYER, OF CHICAGO, ILLINOIS.

ELLIPSOGRAPH.

No. 880,228.

Specification of Letters Patent.

Patented Feb. 25, 1908.

Application filed June 14, 1907. Serial No. 378,953.

To all whom it may concern:

Be it known that I, HENRY LOOYER, citizen of the United States, residing at Chicago, in the county of Cook and State of Illinois, 5 have invented certain new and useful Improvements in Ellipsographs, of which the following is a specification.

My invention relates to mathematical instruments of precision and especially to the 10 class of drafting or drawing appliances, referring particularly to apparatus designed for describing geometrical figures, and arranged expressly for delineating conic sections and allied curves.

15 Instruments for drawing irregular curves have been frequently constructed, but they are usually complicated in their mechanical construction and generally require special skill and experience in the art to enable the 20 operator to manipulate them successfully and in addition to the fault of being cumbersome and unwieldy, their excessive cost has proved a bar to a widely extended use.

To construct oval or elliptical figures with- 25 out the employment of a mechanical aid other than that of the ordinary drafting tools is a slow and unsatisfactory process, since the proper joining of the arbitrary curved segments, and the determination of the centers, 30 when the curves are formed by means of an ordinary compass employing a plurality of centers, require great care and consume a proportionate length of time. The shifting of centers to accommodate the tool to the 35 variations between the major and minor axes of ellipses becomes tedious when many figures have to be laid out and inaccuracy is a frequent result.

The paramount objects of my improve- 40 ments are to produce an instrument adapted to describe elliptical and other irregular curves with accuracy and despatch; to pro- 45 vide an ellipsograph that can be readily applied to any point of the prepared surface upon which the figure is to be delineated, so 50 that the location of the centers may be readily and easily determined and the governing points in the mechanical movements be rapidly shifted as occasion requires; and to supply strong and rigid supports that will afford a minimum obstruction to a proper view of the field of operation.

Further objects of my instrument are to

provide an ellipsograph that can be adjusted so as to enable the axes of ellipses and ovals 55 to be drawn to any desired angle relative to a given base and to permit change of angle and dimensions without shifting the position of the supporting members; and to afford means for changing the relation of some of 60 the guiding elements to produce a more compact form of instrument for the construction of certain classes of irregular curves; to furnish a simple and easily understood applic- 65 ance adapted to the tracing of a large variety 65 of both regular and irregular curves; to pro- vide an instrument having few parts and so 70 designed that some of the members may be folded and other parts dissected to enable the entire instrument to be dismantled and 75 placed in a small compass convenient for stowing in a suitable case. Since the instrument has few parts all designed and con- 80 structed on simple lines, the apparatus can be produced with a minimum outlay for 85 special machinery and because of the econ- 85 omy thus possible in its manufacture, the complete instrument can be supplied at a moderate cost.

Another advantage lies in the mechanical 80 design which will produce smooth and uni- 85 form movements, and as a large proportion of such movements are pivotal the lines will be accurate and well defined. A special 85 feature is made of the graduated scales which are placed wherever they may be required in use and will facilitate the speedy manipula- 90 tion of the mechanism. The main point or focal center, to which the major part of the movements are related, is also the operating 90 point and from this location the various motions are easily controlled.

I accomplish the above and other impor- 95 tant results by the employment of an instru- 100 ment consisting, generally described, of duplicate adjustable standards connected by parallel members upon one of which is mounted a sliding member which carries a tracing bar, and a directing arm having piv- 105 otal connection with a radial lever which revolves in a horizontal plane about the governing center, the latter being supported upon the other of said parallel connecting members, the latter having its continuity broken to permit of an angular and recti- 105 linear movement of said governing center.

The principle of the instrument especially when arranged for tracing ellipses, ovals and circles, may be properly considered as related to that of the trammel, the master center being homologous with the intersection of the grooves of the trammel, and the reciprocating member is analogous to that trammel groove coincident with the major axis of an ellipse. The minor axis groove of 10 the trammel is omitted in this instrument, its function being performed by compound levers, their combined length equaling the distance between the guide pins or blocks which travel in the trammel grooves, the 15 pivotal connection between said levers being the analogue of the median point between the pins of the trammel said point always describing a circular path about the intersection of the major and minor axes, and in 20 a similar way the said pivotal connection of the levers always moves in a circle about the governing or focal center.

The preferred embodiment of my improved ellipsograph is fully illustrated in the 25 accompanying drawing which forms a part of this specification, and in which:—

Figure 1 is a side elevation of the instrument in the position adapted for universal work; Fig. 2 is a top plan view, showing in 30 dotted position certain changes in position of the adjustable members, and the location of the centers, same also dotted, when certain unusual curves are to be traced; Fig. 3 is an elevational view of one of the standards; 35 Figs. 4, 5, and 6, are end, bottom and top views, respectively, of the graduated slide for the governing center; Fig. 7 is a side view of the pivot post for the sliding member, showing the relation of the locking screw; 40 Figs. 8 and 9 are, respectively, front and side views of the tracing stylus or pencil, and Fig. 10 is a side view of a bow pen which may be substituted for the pencil.

Referring to the drawing in detail, the 45 numeral 15 indicates duplicate upright posts or standards each furnished with a base 16, so designed with laterally extending feet as to afford a stable foundation. Each upright is reduced below and received in a 50 socket in the base and may be adjusted vertically by a set screw 17. The posts 15 are provided with apertures 18 suited to receive parallel rectangular connecting members longitudinally adjustable therein and firmly 55 fixed when adjusted by thumb screws 19. The lower connecting member 20 is rectangular in cross section and continuous from standard to standard. The upper connecting member, differs from the lower by having 60 its continuity broken by the interposition of a slotted guiding bar 21, hereinafter described, thus being divided into two bars 22, 23, also rectangular. This form of the structural members affords special security

against torsion and permits the movable or 65 adjustable parts to be fixed in position with ease and certainty. The inner end of the bar 22 is secured to said guiding bar by a thumb screw 24 which can be released so that the connected parts may be swung 70 horizontally as on a pivot. The inner end of the other member or bar 23, on the contrary is removably fixed in a bracket which is formed integral with the guide bar, by a thumb screw 26. By this arrangement, it 75 will thus be seen, the standards 15 and the connecting bars 20, 22, and 23, when their respective thumb screws are tightened, form a rigid framework firmly secured to and supporting the said guide bar 21. The con- 80 tinuous rectangular bar 20 carries a slide 27, which is adapted to reciprocate on said bar with a smooth and easy movement when impelled in the manner to be described. This slide is composed of a body or sleeve 28 85 rectangular in cross section which surrounds the bar 20 and has a set screw 28^a. Upon the side of said sleeve is an extension 29 through which passes a vertical pivot post 30. The head of this post consists of a flat 90 plate which has a bearing upon the upper 95 face of the extension, and carries a rectangular block 31. The lower end of said post 30 extends below the extension where it is received in a box 32. The said box is ad- justably secured to the post by a set screw 33 which has a conical end adapted to engage an annular groove 34 in said post. Through the lower end of the box is passed a tracing 100 rod or bar 35 adjustably secured by a thumb screw 36 and provided with graduations 37. Upon said bar is slidably mounted a stylus 105 holder 38 having a set screw 39 for fixing the holder at any point upon said bar. In order to make it possible to bring the point 110 of the stylus vertically beneath the center of rotation of said post 30 the holder may be furnished with an offset 40 shown in Fig. 9 which will pass beneath the box 32 so that the axial lines of the post and stylus will 115 coincide. A bow pen 41 (Fig. 10) may be substituted for the stylus. The shank 42 of said pen is swiveled in a block 43 adapted to slide upon the tracing rod 35 and has a re- 120 taining cap 44 secured to the end of the shank by a set screw 45. The axis of the pen is inclined to the horizontal plane as shown in Fig. 10 to bring the point of the pen vertically beneath the tracing bar, thus con- 125 ducting to accuracy in the described curve. The said guide bar 21 is provided with a slot 46 in which is slidably mounted a center block consisting of a plate 47 which rests upon the top of said guide bar and is pro- vided upon the under side with a tongue 48 which is received in the slot 46 of the guide bar. One end 49 of the plate 47 is broadened and rounded in circular form and

furnished with graduations 50 around the margin. The rectangular end of the plate is provided with a binding screw 51 by means of which the said plate is firmly locked in 5 any position along the guiding bar, the nut of the screw engaging the under side of the bar. In the center of curvature of the end 49 is a hole 52 through which is passed from the under side a pivot screw 53 having a 10 thumb nut 54 and kept in adjusted position by a lock pin 55. The lower face of the nut is of less diameter than the plate end 49 thus allowing the graduations to be easily read when the nut is in place. The head of the 15 pivot screw is in the form of a plate 55^a carrying a box or sleeve 56 apertured to receive a rectangular arm 57 which is furnished with graduations 58 and locked in the sleeve by a set screw 59. The distal end of the said arm 20 is pivoted at 60 to the end of a companion arm 61 the other end of which is received in a suitable aperture in the said rectangular box 31 which is formed integral with the pivot post 30, previously described, and is 25 adjustably held therein by a set screw 62.

The guide bar 21 may be used in two positions shown in full and dotted lines, respectively, in Fig. 2. To change from one position to the other it is necessary to remove the 30 sectional bar 23 and release the thumb screw 24, upon doing which the said bar can be swung on the center 24 to either of the indicated positions. A clip or box 63 is secured to one end of the guide bar, and when the latter is turned to its position parallel to the connecting bar, as shown in dotted lines in Fig. 2, said box forms a socket for the reception of the inner end of the rod 23, which is now replaced and fixed by its set screws to 35 form a support as before. The upper margin of the sleeve 32 is provided with graduations 64 and an index mark 65 is impressed upon the extension 29. One side of the bar 21 is furnished with graduations 66 to facilitate the location of the slide block therein.

The method of using my improved instrument for tracing curves is very simple and readily understood so that it can be operated by one not skilled in the use of instruments 50 of precision. The apparatus having been set up in the manner shown and the center of the curve to be described having been determined, the instrument is moved until a vertical line through the axis of the pivot 55 screw 53 will coincide with the selected location for the curve center. This pivot screw may be termed the master center, for it governs the movements of the levers, locates the centers of the curves, determines the angle 60 of inclination of axes, both major and minor, and is the point to which all the most important mechanical movements are referred. The operator impels the tracer by turning the thumb nut 54 with one hand while the

other is applied to the pencil holder or slide 65 block. The mechanical movements are governed chiefly by the hand that grasps the nut 54, the force at the block or stylus being only applied in passing the dead center which occur when the slide 27 is at the median line. 70 When the pen illustrated in Fig. 10 is employed the swivel cap 44 is held between the fingers and rotated slightly as the pen travels the object being to keep the flat of the nib tangent to the curve throughout its course 75 in order to get the best results.

In Fig. 2 the tracing bar 35 is shown parallel to the connecting bar 20. The instrument is in a position to describe an ellipse, the major axis of which will be at a right 80 angle to the initial direction of said bars 20 and 35, the axis of the pivot post and that of the stylus being at the opposite extremities of the minor axis. Under these conditions the manipulation of the mechanism 85 and the movement would be as follows: We will suppose the thumb nut to be rotated clock-wise by one hand, the arm 57 will move the center 60 in the same direction circumferentially about the main center 53, and the 90 arm 61 will make traction upon the slide 27 causing it to travel towards the main center upon its slide-way, the rod 20. The stylus will travel in an opposite direction about its center 30 and when this center has arrived 95 beneath the center 53, the several bars 35, 57 and 61 will lie in the same vertical plane coincident with the major axis of the ellipse. Thus a fourth part of the curve will have been described. By further manipulation 100 of the thumb nut and the tracer the slide will be carried on beyond the median line and the movements will continue until another fourth will have been completed. The several movable arms will again lie parallel with the connecting bar and the pencil 105 will be found to have changed places with the pivot point. A continuation of the operation will carry the stylus through the remaining half of the figures. Thus in tracing ellipses the center 60 will always travel in a circle about the master center, the center 30 describe a right line, and the stylus will move in a true elliptical path and in a direction inverse to that of the center 60.

To change the direction of the axes of the ellipse it is only necessary as the preliminary step, to loosen the screw 33 and swing the tracing bar around its center to the desired location, it being understood that the major 120 axis will lie at a right angle to a line intersecting the pencil and the main center.

To draw cycloids and epicycloidal curves it is necessary that the guide bar 21 be in the position shown in full lines in Fig. 2. To 125 describe a cycloidal curve the slide 47 is moved to some point *a*, shown in dotted lines, the slide center moved to a point *b*.

When the tracing bar 37 coincides with the bar 61, the point *c*, must lie equi-distant from the tracing point *d* and the slide center *b*. Operating the thumb nut 54 and the tracing bar, as before explained, will drive the tracer in an epicycloidal path.

In order to trace a circle the slide 27 is brought to the median line and the set screw 28^a tightened when the axes of the centers 5 53 and 30 coincide, so as to prevent any sliding movement of the center 30 during the operation of tracing the circle. The pencil having been located at the radial distance from the coincident centers, the operation 10 of the thumb screw will carry the tracer circumferentially in a true circle the center of the circle coinciding with the master center. The instrument will describe a theoretically straight line, and the adjustments will permit of such an arrangement as will result in 15 the projection upon the prepared surface of a theoretical point.

To describe a right line the pencil holder shown in Figs. 8 and 9, is substituted for the 20 straight form, and this is brought into apposition with the slide 27, so that the axes of the slide-center and that of the pencil will coincide. Rotation of the thumb screw at the main center will now cause the slide to 25 move upon its guide rod 20 and as the pencil point is coincident with the center 30, which always moves in a right line, the resulting delineation will be a straight line subject of course to the minute errors incident to all 30 mechanical and physical contrivances. It will be noted that the center 30 always revolves, and in this case the pencil will partake of this movement making one half of a revolution in traveling from the initial point 35 to the limitation of its path, the thumb nut also making but half a turn. If the turn were completed, or if made in a reverse direction the pencil will make a retrograde movement over the line previously traced.

To project a point upon the paper or table 40 the centers 38 and 30 are brought into coincidence as if for tracing a circle, the centers thus combined then located beneath the main, or master center, and the slide 28 locked upon its bar by the set screw 28^a. The rotation of the thumb screw will then cause the center 30 to rotate and the tracer which coincides therewith will revolve in unison with said center 30 and as it has no 45 radial movement the tracer will inscribe a point or dot coincident with the mechanical, and theoretically with the mathematical center.

The function of the graduations 50 at the 50 master center is to determine the angular position of the axes of any traced curve, and for describing a given portion of a figure.

The vertical adjustability of the standards will be found very useful in many cases and

especially when the center of the curve is located adjacent to a margin of the drafting board upon which tracings are commonly made. Under such circumstances one support may be placed upon the board or paper, and the base of the other can rest upon the 70 table or bench beside the board and the post adjusted to the paper height to level the connecting bars.

Having thus described my invention what I claim as new and desire to secure by Letters 75 Patent, is:—

1. An apparatus for the purpose specified, including a pivoted slideway, an operating member mounted in said slide-way, a slide adapted to be reciprocated in a right line, a tracing bar attached to said slide and adapted to be adjusted circumferentially, and operative means connecting the slide with said member.

2. An apparatus for the purpose specified 85 including supports, a sliding member adapted to be reciprocated in a right line, a tracing bar pivotally attached to the said sliding member, an operating member, means for sliding said operating member upon its support and means for simultaneously reciprocating said sliding member and rotating said tracing bar upon its pivot.

3. An apparatus for the purpose specified, 95 including adjustable standards, means connecting the standards, a slidable member adapted to be reciprocated in a right line, a tracing member pivotally connected with said slidable member, an operating member mounted upon a slide, means for adjusting the operating member on said slide, said operating member being adapted to simultaneously reciprocate said sliding member and rotate the said tracing bar upon its center.

4. An apparatus for the purpose specified, including adjustable standards, a plurality of bars connecting the standards, a slide adapted to reciprocate upon one of said bars, an operating member mounted upon a 100 pivoted slide frame means for adjusting said slide frame upon its pivot, means for adjusting said operating member upon its slide-frame, operative connection between said member and said slide, and a tracing bar 115 pivotally connected with said slide and adapted to be rotated upon its pivot synchronously with the reciprocation of said slide.

5. An apparatus for the purpose specified, 120 including adjustable standards, a plurality of adjustable bars connecting the standards, a slide adapted to reciprocate upon one of said bars, an operating member adapted to move said slide longitudinally, means for fixing 125 said slide in selected positions upon its way, a tracing bar pivotally connected with the slide and adapted to be rotated upon its

pivot synchronously with the movement of said slide, and means for adjusting said tracing bar circumferentially about its pivot.

6. An apparatus for describing regular and irregular curves, including a centrally located operating member, a sliding member, a tracing bar pivotally mounted in said sliding member, an arm adjustably fixed to said operating member, and a lever connected to the pivot of said tracing bar and having pivotal connection with said arm.

7. An apparatus for describing regular and irregular curves, including a centrally located rotatable operating member, a slide for said member, said slide adapted to swing upon a pivot a slidable member carrying a pivotally mounted tracing bar and means for reciprocating said sliding member by the rotation of said operating member.

8. An apparatus for describing geometrical figures, including a lever centrally pivoted, means for rotating said lever about its pivot, a slide-way for said pivot, means for adjusting said pivot in said slide-way a slide adapted to be moved in a right line in a path intersecting the prolongation of the axis of said pivot, and a tracing bar pivoted in said slide and having an arm pivotally connected with the free end of said centrally pivoted lever.

9. An apparatus for describing geometrical figures including a plurality of adjustable supports, adjustable bars connecting said supports, a slotted guide bar, a block adapted to slide in said guide bar, a lever pivoted to said blocks, means for manually rotating said lever, a slide adapted to move in a right line, a tracing member pivoted in said slide, an arm fixed to the pivot in said slide and having pivotal connection with the said lever.

10. An apparatus for describing curves including a movable focal center, a slide way for said focal point, a lever adjustably mounted to rotate on said focal center, a sliding center, a graduated tracing bar adjustably mounted in said sliding center, and an adjustable arm pivotally connecting said tracing bar with said lever, and means for varying the angle between said tracing bar and said adjustable arm.

11. An apparatus for describing curves, including a movable focal center, a lever pivoted at said focal center and provided with graduations, a tracing bar pivotally mounted, and means for moving said tracing bar upon its pivot, said means consisting of a graduated arm adjustably secured to said pivot and having a pivotal connection with the said lever.

12. An apparatus for describing geometrical figures, including duplicate adjustable standards, a slotted adjustable guide-bar supported upon said standards, a center adapted to slide in said guide bar, a gradu-

ated lever pivoted at said center and adapted to be manually revolved on its pivot, a slide adapted to be moved in a linear direction, and having an adjustable graduated tracing bar pivoted thereto, an arm pivotally connecting said tracing bar with said graduated lever, means for varying the angle between the tracing bar and said arm, said means being provided with a scale for indicating the angular deviation of said arm and bar.

13. An apparatus for describing geometrical figures, including duplicate adjustable standards, a slotted adjustable guide bar, a center adapted to slide in the guide bar, said guide-bar having graduations for indicating the longitudinal adjustment of said center, a graduated lever pivoted at said center and adapted to be manually revolved upon its pivot, a slide adapted to be impelled in a linear path and carrying a graduated adjustable tracing bar pivoted thereto, an arm pivotally connecting said tracing bar with said graduated lever, means for varying the angle between the tracing bar and said arm, and an adjustable stylus mounted upon the said tracing arm, and provided with an offset.

14. An apparatus for describing geometrical figures, including a slotted adjustable guide bar, a center adapted to slide in said bar, and having a rotatable axis mounted therein, said center being provided with graduations for determining the angular position of its axial attachments, a graduated lever adjustably mounted upon said axis, a slidable center adapted to move in a linear path, a pivot post mounted at said slidable center and provided with an adjustable graduated arm having pivotal connection with said graduated lever, a tracing bar adjustably attached to said pivot post and adapted to be adjusted circumferentially about its center, and an adjustable stylus mounted upon said tracing bar and adapted to be placed so that its axis will coincide with the axis of said pivot post.

15. An apparatus for describing geometrical figures, including a foldable guide-bar, a center adapted to slide in said bar and carrying an axially mounted pivot provided with graduations for determining its angular position, a graduated lever carried upon said axis, a slidable center adapted to move in a linear path, means for securing said slidable center from lateral movement, a pivot post mounted in said slidable center, an adjustable graduated arm attached to said post and having pivotal connection with said graduated lever, a tracing bar detachably connected to said post and adapted to be adjusted circumferentially about its center of revolution and an adjustable stylus carried on said tracing bar.

16. An apparatus for tracing geometrical figures, including a focal center, means for sliding said center in a horizontal plane, a

sliding center adapted to be moved in a linear path, a tracing member adapted to be placed so that its axis will correspond with the axis of said sliding center, and means for bringing the axes of said tracing member and said sliding center into coincidence with the said focal center.

In testimony whereof I affix my signature in the presence of two witnesses.

HENRY LOOYER.
